UNITED STATES PATENT OFFICE.

MARTIN V. HAMMACK, OF THALIA, VIRGINIA, ASSIGNOR OF ONE-HALF TO
CEPHAS O. GRIMES, OF PORTSMOUTH, VIRGINIA.

DESIGN FOR A BEDSTEAD.

SPECIFICATION forming part of Design No. 35,933, dated June 3, 1902.

Application filed March 29, 1902. Serial No. 100,627. Term of patent 7 years.

To all whom it may concern:

Be it known that I, MARTIN V. HAMMACK, a citizen of the United States, residing at Thalia, in the county of Princess Anne and State of Virginia, have invented a certain new and useful Design for Bedsteads, of which the following is a specification.

My said invention consists in a design for bedsteads, whereby a bedstead is provided having a head and foot board of an attractive and ornamental character.

The accompanying drawing represents a bedstead having a head and foot board of my said design.

The design of the headboard consists of the metallic frame A of substantially the form shown, being in the form of a compound curve on each side and at the top joined by oval or semicircular corners. In each upper corner is formed a circle or ring 1, in which is a star. In the center at the top is a ring 2, within which is a crescent and a star. Within the outside frame A is mounted a large ring 3, supported from said frame A by means of a series of connecting-bars a' at intervals around its edge. At a distance within said ring 3 is another ring 4, supported from said ring 3 by a series of radial connecting-bars a' , arranged at regular intervals. Within each of the spaces between said bars a' is a ring 5, and within each of said rings is a representation of a star. Within ring 4 is a centerpiece 6, which has an ornamental design on its surface outlining or indicating star-points. Said

centerpiece is surrounded by a ring 6, between which and the ring 4 extend numerous star-points 7, points of which are joined to said ring 4, whereby said centerpiece is supported. The ring 6 on said centerpiece serves as a frame for the ornamental design on said centerpiece. The rings 5 also serve as frames for the designs within them. In each lower corner of the frame is mounted a rosette 8, supported between the frame and the ring 3 by connecting-bars a' . The footboard is of the same general form in outline, having rings 9 in each of its top corners containing a star and a ring 10 in its center containing a crescent and a star, making the upper portion of the footboard of a design to correspond with the upper portion of the headboard. Beneath said ring 10 is a larger ring 11 containing a star, and on each side of said ring 11 a smaller ring 12 containing a star, said rings being supported from the frame of said footboard by connecting-bars a' .

Having thus fully described my said invention, what I claim as new, and desire to secure by Letters Patent, is—

The design for a bedstead substantially as herein shown and described.

In witness whereof I have hereunto set my hand and seal, at Washington, District of Columbia, this 26th day of March, A. D. 1902.

MARTIN V. HAMMACK. [L. S.]
